UNITED STATES PATENT OFFICE.

GEORGE LANE, OF BETHEL, CONNECTICUT.

HAT-SUPPORT AND PACKING-RING.

SPECIFICATION forming part of Letters Patent No. 399,201, dated March 5, 1889.

Application filed July 27, 1888. Serial No. 281,222. (No model.)

To all whom it may concern:

Be it known that I, GEORGE LANE, a citizen of the United States, residing at Bethel, in the county of Fairfield and State of Connecticut, 5 have invented certain new and useful Improvements in Combined Hat-Supports and Packing-Rings; and I do hereby declare the following to be a full, clear, and exact description of the invention, such as will enable 10 others skilled in the art to which it appertains to make and use the same.

My invention has reference to certain improvements in combined hat-supports and packing-rings, and has for its object to provide 15 an exceedingly simple and effective device of this description; and with this end in view my invention consists in the details of construction and combination of elements hereinafter fully set forth, and then specifically designated by the claims.

In the accompanying drawings, Figure 1 is a side elevation showing a series of hats supported and packed within a bandbox by means of my improvement; Fig. 2, a plan view 25 of the same, and Fig. 3 a detail plan of one of my improved combined supports and rings.

Similar letters denote like parts in the several figures.

A is a flat ring made from ordinary paste 30 or straw board, or, in fact, from any light and cheap material. The opening of this ring is large enough to admit a hat-crown without contact with the latter.

B is a strip of cloth, paper, or any flexible 35 material pasted or otherwise secured to opposite sides of said ring in such manner that the portion of said material which crosses or bridges the opening of the ring is slack, and depends so as to afford a sling or cradle for 40 supporting the hat-crown, as will be presently set forth.

In a series of hats packed and supported as shown at Fig. 1, the flat ring rests against the under side of the brim of a hat, while a 45 flexible strip, B, hangs within the crown of

said hat and supports the tip of the crown of the succeeding hat. I prefer to let the ends of the strip B extend beyond the ring, so as to overhang the hat-brim, for the purpose of preventing chafing of the latter against the 50 sides of the packing-box C.

The diameter of the ring is a trifle less than the diameter of the packing-box, so that said ring is confined as against any wobbling within the box, thus effectually preventing the 55 packed hats from becoming displaced or tumbled during shipment. It will be seen that I have overcome the most serious objection common to hat-packing rings—namely, the chafing of the upper face of the hat-brim— 60 and this is solely due to the fact that my ring and support have no contact whatever with this part of the brim.

I claim—

1. A combined ring and support for packing hats, consisting of a flat ring and a flexible strip bridging said ring and secured to opposite sides of the latter, substantially as set forth.

2. The combination, with the flat ring approximately corresponding in diameter to the diameter of the hat-packing box, of the flexible strip depending through the opening of said ring and secured to opposite sides of the latter, substantially as and for the purposes 75 set forth.

3. The combination, with the flat ring resting against the under face of the hat-brim and admitting the crown-tip of a succeeding hat, of a flexible strip secured to opposite 80 sides of said ring and depending through the ring, whereby a support is afforded for said crown, substantially as shown and described.

In testimony whereof I affix my signature in the presence of two witnesses.

GEORGE LANE.
